DESIGN FOR A MEDALLION OR SIMILAR ARTICLE

Frances K. Johnston, New York, N. Y.

Application June 19, 1934, Serial No. 52,234

Term of patent 3½ years

To all whom it may concern:

Be it known that I, FRANCES K. JOHNSTON, a citizen of Canada, and resident of New York, in the county of New York and State of New York, have invented a new, original, and ornamental Design for a Medallion or Similar Article, of which the following is a specification, reference being had to the accompanying drawing, forming part thereof.

In the drawing:

Fig. 1 is a face view of a medallion showing my new design, a portion only of the border being illustrated which is continued throughout the extent thereof.

Fig. 2 is a side view illustrating a portion of the border on the side of the medallion which is continued throughout the extent thereof.

I claim:

The ornamental design for a medallion or similar article, substantially as shown and described.

FRANCES K. JOHNSTON.
